MAGNETIC TAPE TRANSPORT

Albert W. Martin, Belmont, George D. Rehklau, Los Altos, Noland E. Vogt, Menlo Park, and Roger H. Whitlock, Los Altos, Calif., assignors to Ampex Corporation, Redwood City, Calif., a corporation of California

Filed Sept. 21, 1964, Ser. No. 81,811

Term of patent 14 years

(Cl. D26—5)

FIG. 1

Des. 202,344

PAGE 2

FIG. 2

Des. 202,344

PAGE 3

FIG. 3

FIG. 4

FIGURE 1 is a front, top and right side perspective view of a magnetic tape transport, showing our new design;

FIGURE 2 is a left side elevational view;

FIGURE 3 is a rear elevational view; and

FIGURE 4 is a top plan view thereof.

The grille fragmentarily indicated by vertical dash lines is continuous within the boundaries indicated.

The dominant features of our new design are shown in solid lines in the drawing.

We claim:

The ornamental design for a magnetic tape transport, substantially as shown and described.
